UNITED STATES PATENT OFFICE.

CARL DONNER, OF FRANKFORT-ON-THE-MAIN, GERMANY.

MACHINE FOR REMOVING DOWN OR PULLINGS FROM FUR OR PELTS.

SPECIFICATION forming part of Letters Patent No. 679,835, dated August 6, 1901.

Application filed April 6, 1901. Serial No. 54,573. (No model.)

To all whom it may concern:

Be it known that I, CARL DONNER, a subject of the Emperor of Germany, residing at Durerstrasse 13, Frankfort-on-the-Main, in 5 the German Empire, have invented certain new and useful Improvements in Machines for Removing Down or Pullings from Fur or Pelts, (for which I have applied for Letters Patent in Germany, application H. 20,704 10 IV/28^b, dated October 8, 1900; in England, application for Provisional Patent No. 18,276, dated October 13, 1900; in France, application No. 292,967, dated October 17, 1900; in Belgium, application No. 120,908, dated October 22, 1900, and in Italy, application No. 912, dated October 22, 1900,) of which the following is a specification.

My invention relates to machines for removing "down" or "pullings" from pelts; 20 and the machine constituting the subject-matter of my invention is particularly adapted for removing pullings from coney and like pelts before the pelts have been dyed or otherwise treated.

25 The object of my invention is to provide a machine for doing mechanically what heretofore could only be successfully and efficiently accomplished by hand.

To these ends my invention consists in the 30 novel arrangement and combination of parts hereinafter described and claimed.

In the accompanying drawings, Figure 1 is a vertical sectional view of one form of machine embodying my invention. Fig. 2 is a 35 front elevation of the same. Figs. 3, 4, and 5 are diagrammatic views of portions of the structure to be hereinafter described. Fig. 6 is a perspective view of a piece of coney-pelt, the view showing a portion of the pelt 40 in its natural state with the pullings in place and another portion of the pelt with the pullings removed. Fig. 7 is an enlarged detail diagrammatic side view of several individual hairs of a coney or like pelt projecting from 45 the skin. Fig. 8 is a diagrammatic vertical sectional view of a portion of the machine, showing the manner in which the pullings are removed.

In order that a thorough understanding of 50 the present invention may be arrived at, I consider it desirable to briefly describe the manner heretofore employed of removing

pullings from coney and like pelts. The Australian, French, and, in fact, all coney-pelts have peculiar characteristics. Each of the 55 individual body-hairs of the pelt is composed of two portions, which are distinctly different in their physical characteristics. That portion of the hair which is next to the skin 1 and which is known as "fur" or "ground-hair" is indicated at 2 in Figs. 6, 7, and 8 of the drawings. This fur is soft and velvety and extends to a considerable distance from the skin and terminates at 3, where each so-called "ground-hair" joins another portion, 60 that is indicated at 4 and is known as "hair" or "pullings." These pullings 4 are when compared with the fur 2 stiff and coarse, and presenting, as they do, the outer surface of the pelt constitute an undesirable element 70 thereof, which detracts from its value.

Heretofore it has been customary to remove the pullings by running a pelt through a machine provided with a plurality of rotating knives. These knives were brought into 75 contact with the haired surface of the pelt and cut the pullings off. In practice, however, it was found that in order to assure the removal of all the pullings from the pelt it was necessary to cut to a considerable depth 80 into and to remove a portion of the fur, thereby reducing the value of the pelt. This disadvantage was so great that it was found desirable and necessary in order to produce a better finished product to employ hand 85 labor. In removing the pullings by hand the operator employs a small knife and cuts the pullings from the fur as near as possible on the plane 3, where the fur 2 joins the hair 4. This last method is an expensive, unsatisfactory, and tiresome one, inasmuch as the operator can cut and remove but a few pullings at a time and must continue in this manner until the entire pelt has been finished. By my present invention I overcome all of 95 the disadvantages heretofore encountered and provide a simple machine which will readily and efficiently remove the pullings from the fur where the two are joined, and without injuring the fur. 100

In the drawings, wherein like reference characters indicate like parts in the various views, *a* indicates a frame, which may support a suitable box or housing *b*. This hous-

ing communicates with a suitable suction or exhaust apparatus *c*, by means of which the pullings are collected and discharged through a suitable channel or pipe *d*. Contained 5 within the housing *b* is a roller *e*, that is corrugated longitudinally throughout its length, so as to present a series of rounded ribs *f*. This roller is made of rubber or other suitable elastic material and is positively driven 10 by suitable means. In the present instance I have shown a pulley *g* connected to the shaft *h* of said roller, and this pulley is operatively connected by the belt *i* to the driving-pulley *j*, carried by the main shaft *k*. This 15 main driving-shaft *k* may likewise be provided with a pulley *l*, over which the belt *m* passes in order to drive the pulley *n* of the exhaust or suction apparatus *c*. Coöperating with the roller *e* is a second elastic roller 20 *o*, which preferably has a smooth periphery and is mounted to rotate freely in its bearings. This roller *o* is preferably of much smaller diameter than the roller *e* and is mounted and maintained in such position 25 that a compressing action is exerted between the rib *f* and the roller *o* when the former is rotated in the direction of the arrow in Fig. 1. The roller *o* is mounted in bearings in a plate or support *p*, which is adjustably secured 30 in place by suitable means, as indicated at *q*. By reason of this adjustment of the support for the roller *o* the roller *o* can be moved toward and away from the roller *e*, so that a greater or less compression may be exerted 35 between these rollers in the rotation of the roller *e*. The adjustment is not radial with reference to the roller *e* and can therefore be made with greater accuracy. In order to bring the pelts to the coöperating-rollers 40 *e o*, the housing *b* is apertured throughout the lengths of these rollers, as indicated at *r*, and the frame *s* is pivoted at *t* to the framing of the machine and is provided at its upper end with a bar or guide *u*, upon which the pelts are 45 adapted to be supported. The movement of the frame *s* toward the bight of the rollers will carry the belt to a position where the pullings 4 thereon may be caught between the rollers, as indicated diagrammatically in Fig. 8 of the 50 drawings. When the pullings 4 are caught between the rollers *e* and *o*, they are first engaged as indicated in Fig. 3 and then compressed with sufficient force to tear or separate them from the fur 2, as indicated in Fig. 55 4. The pullings will be collected in the housing *b* and conveyed by the suction device through the delivery-tube *d* to a suitable receptacle. It will be observed that as the pelt is fed along the pullings are progressively 60 torn from the fur and the soft fur will be exposed, as indicated at the right-hand portion of Fig. 6 of the drawings.

The pullings, which constitute a valuable

by-product, are removed from the pelt and may, with the aid of my machine, be collected and conveyed mechanically to a suitable receptacle. It may be found necessary to feed the pelt throughout its entire length several times over the guide *u* in front of the rollers in order to remove all of the pullings from 70 the fur.

Confusion should not exist as to the function and purpose of my machine. Machines have been previously devised for entirely removing or pulling bodily so-called "water-hairs" from the skin. Water-hairs do not possess the same physical characteristics as what I have designated as the "body-hairs" of the pelt and which I have attempted to illustrate in the accompanying drawings. 80 These machines for removing water-hairs have nothing in common with my invention and are intended to operate upon the pelt after the pullings have been removed by one of the processes hereinbefore described and after 85 the pelt has been dyed.

Having described my invention, what I claim, and desire to secure by Letters Patent, is—

1. The combination of an elastic roller, a 90 second roller mounted to rotate about an axis parallel to that of the first-named roller, said second roller being adjustable in a direction at an angle to a radial line connecting the centers of the two rollers, longitudinal bodily 95 elastic ribs or corrugations on the second roller, and means for holding a pelt adjacent to the bight of the two rollers.

2. The combination of two rollers, one having a smooth elastic surface and the other 100 rounded longitudinal elastic ribs or corrugations, one of the rollers being adjustable in a direction at an angle to a radial line connecting the centers of the two rollers, and means for holding a pelt adjacent to the bight of the 105 two rollers.

3. The combination of two rollers of materially-different sizes, one of them having a substantially cylindrical elastic surface and the other longitudinal bodily elastic ribs or 110 corrugations, one of the rollers being adjustable in a direction at an angle to a radial line connecting the centers of the two rollers, and means for holding a pelt adjacent to the bight of the two rollers.

4. The combination of two rollers one having longitudinal elastic ribs or corrugations and the other a substantially cylindrical elastic surface, the latter roller being adjustable in a direction at an angle to a radial line connecting the centers of the two rollers.

CARL DONNER.
